UNITED STATES PATENT OFFICE

163,050

TROUSERS RACK OR SIMILAR ARTICLE

Albert Leebow, East Rockaway, N. Y., assignor to
Berkeley Industries, Jersey City, N. J., a corporation of New Jersey

Application August 10, 1949, Serial No. 4,401

Term of patent 14 years

(Cl. D33—8)

To all whom it may concern:

Be it known that I, Albert Leebow, a citizen of the United States, and a resident of East Rockaway, New York, have invented a new, original, and ornamental Design for Trouser Rack or Similar Article, of which the following is a specification, reference being had to the accompanying drawing, forming a part hereof, in which

Figure 1 is a perspective view of a trousers rack or similar article in extended position, showing my new design; and

Figure 2 is a front elevational view thereof, in folded position.

I claim:

The ornamental design for a trousers rack or similar article, as shown.

ALBERT LEEBOW.
